UNITED STATES PATENT OFFICE

171,072

HANDBAG

Sheldon J. Aberman, Miami Beach, Fla.

Application August 6, 1953, Serial No. 26,298

Term of patent 3½ years

(Cl. D87—3)

To all whom it may concern:

Be it known that I, Sheldon J. Aberman, a citizen of the United States of America, residing in Miami Beach, county of Dade, and State of Florida, have invented a new, original, and ornamental Design for a Handbag, of which the following is a specification, reference being had to the accompanying drawing, forming part thereof, wherein:

Figure 1 is a front perspective view of a handbag showing my new design, with the handles in separated position.

drawn to a smaller scale, and showing the handles in a closed position.

The side not shown in Figure 1 is identical to the side shown.

I claim:

The ornamental design for a handbag, substantially as shown and described.

SHELDON J. ABERMAN.
